UNITED STATES PATENT OFFICE.

JOHN PATRICK GRIMLEY, OF HARRISON, NEW JERSEY, ASSIGNOR TO SAMUEL J. RAWLINGS, OF KEARNY, NEW JERSEY.

DOOR HOLDER.

Application filed January 14, 1926. Serial No. 31,273.

This invention relates to a door holder and it is an object of the invention to provide a device of this kind which operates to hold the door ajar as when providing for effective ventilation of a room and particularly a cabin or stateroom of a marine vessel although it can be employed with equal facility in connection with a door of a dwelling or other building.

10 It is also an object of the invention to provide a device of this kind for holding a door ajar and in a manner to prevent such means being rendered inoperative to permit full opening of the door by a person outside of 15 the room.

Another object of the invention is to provide a holder of this kind for effectively maintaining a door ajar, said holder comprising a structure whereby the same may 20 be rendered inoperative or released from the door when the door is in full closed position.

The invention consists in the details of construction and in the combination and arrangement of the several parts of my improved door holder whereby certain important advantages are attained and the device rendered simpler, less expensive and otherwise more convenient and advantageous for 30 use, as will be hereinafter more fully set forth.

The novel features of my invention will hereinafter be definitely claimed:

In order that my invention may be the better understood, I will now proceed to describe the same with reference to the accompanying drawings, wherein:

Figure 1 is a view partly in section and partly in top plan illustrating a holder constructed in accordance with an embodiment of my invention, the door being shown in full closed position and a second position of the swinging arm being indicated by broken lines;

45 Figure 2 is a view similar to Figure 1 with the door in an ajar position;

Figure 3 is an enlarged fragmentary view partly in section and partly in top plan illustrating certain details of construction as 50 comprised in my improved holder as herein set forth;

Figure 4 is a fragmentary view in front elevation of the structure illustrated in Figure 3;

55 Figure 5 is a fragmentary view partly in

vertical section and partly in side elevation illustrating in detail the connection herein disclosed between the swinging slotted arm and the door, a second position of the arm proper being indicated by broken lines;

60 Figure 6 is a view similar to Figure 5 showing the arm in its lowered or dropped position;

Figure 7 is a view in end elevation of the sliding bolt and its supporting bracket.

65 As disclosed in the accompanying drawings, W denotes a wall provided with a conventional door opening with which coacts in a well known manner a swinging door D opening into the room.

70 Secured by the screws 1 or the like to the inner face of the door at a preferred point along its free vertical marginal portion is the base plate 2 of a bracket B. The bracket also includes a web 3 extending outwardly 75 from the plate 2 and provided at its outer end with the barrel 4 open at its opposite ends, said barrel being disposed in a direction transversely of the door D when the bracket B is in applied position with its outer end, as herein disclosed, extending slightly beyond the free vertical edge of the door.

75 The outer wall of the barrel 4 is provided with the longitudinally spaced spiral grooves 5. The grooves 5 are reversely related so that a single bracket may be employed with equal facility at either the right or left vertical portion of the door D.

80 Slidably engaged within the barrel 4 is a bolt 6. The outer end of the bolt 6 at its axial center is provided with a forwardly directed reduced extension or pin 7 provided at its outer end with an enlargement or head 8 herein disclosed as of a disk-like 85 form. An operating rod 9 is engaged with the bolt 6 through a slot 5 of the barrel 4 so that upon swinging movement of the rod 9, the cam action afforded by the side walls of such slot 5 will either extend or retract 100 the bolt 6.

85 Secured to the wall W by the screws 10 or the like is a plate 11, said plate being aligned with the plate 2 of the applied bracket B when the door D is in its full 105 closed position. This plate 11 is spaced a desired distance from the adjacent jamb of the door opening and is provided with an extension 12 disposed toward the door opening. The major portion of the extension 110

is undercut to provide what might be termed an internal recess or chamber 14, said recess or chamber also partially extending within the plate 11 proper as is clearly indicated in Figure 3. The extension 12 is also provided in its central part with an opening or slot 15 affording communication to the recess or chamber 14 and the opposite sides of said opening 15 are defined by the outstanding lugs 16 which provide a mounting for the pivot pin 17. Substantially snugly fitting between the lugs 16 is a sleeve 18 freely mounted upon the pivot pin 17 whereby the sleeve 18 is capable of swinging or oscillating movement, the extent of which being limited by the outstanding and diametrically opposed lugs 19 carried by the sleeve 18 and having contact with the outer faces of the plate 11 and its extension 12. This limited swinging or oscillating movement of the sleeve 18 is in a direction toward or from the door opening.

At a point substantially midway between the lugs 19, the sleeve 18 is provided with the outstanding flat head 20 the axis of which being at right angles to the axis of the sleeve 18. Straddling this head 20 are the outstanding spaced ears 21 carried by the inner end of the elongated arm 22, said ears 21 being pivotally connected with the head 20 through the medium of the pivot member 23. The pivot member 23 is disposed at right angles to the pivot pin 17 whereby the arm 22 is supported for swinging movement in a vertical direction. The arm 22 has unhindered swinging movement in a downward direction into substantially a vertical position as illustrated in Figure 6, such limit of downward movement being effected by contact of the hinged end portion of the arm 22 with the lowermost lug 16. The head 20 is provided with a vertically disposed and substantially straight edge face 24 with which the pivoted end portion of the arm 22 contacts upon upward swinging movement of said arm, such contact holding the arm 22 against movement up beyond a substantially horizontal center. The arm 22 may be disposed on a suitable curvature and is provided substantially the entire length thereof with a slot 25 of a width to receive the reduced extension or pin 7 of the bolt 6 but of a width less than the major diameter of the enlargement or head 8. The inner end, however, of the slot 25 is enlarged, as at 26, to readily permit said enlargement or head 8 to pass therethrough.

When the various parts of my improved holder are in applied or working position, the enlargement or head 8 of the bolt 6 can only be inserted through the enlarged end portion 26 of the slot 25 when the door D is in its completely closed position.

When it is desired to swing the door into full open position, the arm 22 is separated

from the bolt 6 and caused to permit its downward position as illustrated in Figure 6 but, when it is desired to hold the door in an ajar position, the door is completely closed whereupon the arm 22 may be adjusted to pass the enlargement or head 8 of the bolt 6 through the enlarged portion 26 of the slot 25 provided in the arm 22. At this time, it is also to be understood that the rod 9 has been operated to project the reduced extension or pin 7 carried by the bolt 6. As the door D is swung ajar as desired, the extension or pin 7 will ride outwardly along the slot 25 and when the required position of the door is obtained the rod 9 is forced upwardly with the resultant action of retracting the bolt 6 and causing the enlargement or head 8 of the bolt to coact with the adjacent end of the barrel 4 to effectively clamp the arm 22 and thus maintain the door in such position. It will be understood that the door may be held in an ajar position at any point along the slot 25 of the arm 22.

The lugs 19 or wings, which they may be called, provide means, as hereinbefore stated, to limit the swinging movement of the sleeve 18. This is of particular advantage as it prevents any part directly associated with said sleeve from being moved into position to hinder or obstruct the requisite swinging movement of the door D. The oppositely directed lugs or wings 19 are employed so that the arm 22 may be mounted at either side of a door opening as may be required.

While in the accompanying drawings I have illustrated the rod 9 as swinging downwardly with respect to the barrel 4, it will be understood that the same can be employed with equal facility if arranged to swing upwardly and in which event the requisite clamping action will be upon the arm 22 when the rod is extending outwardly from the barrel 4 in substantially a horizontal direction and disposed in an upward vertical direction when the reduced extension or pin 7 is extended.

To the under surface of the outer wall of the recess or chamber 14 is secured an extremity of a flat spring 27 the free end portion of which pressing against the inner peripheral portion of the sleeve 18 whereby said spring 27 serves as a brake to stop any loose motion that may be liable to occur.

With a door held ajar through the medium of one of my improved devices, it will be obvious that the door cannot be further opened from without to permit unauthorized entry as the arm 22, as hereinbefore stated, can only be separated or disengaged from the bolt 6 when the door D is completely closed.

From the foregoing description it is though to be obvious that a door holder constructed in accordance with my inven-

tion is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. In combination with a wall having an opening, a swinging closure member therefor, a member rotatably supported by the wall adjacent to the opening, an elongated arm pivotally connected with said second member, said arm having swinging movement about its pivot in a direction angular to the swinging movement of the second member about its pivot, a sliding bolt carried by the closure member, said arm being provided with an elongated slot through which the bolt is adapted to extend when projected, said projected portion of the bolt comprising an outstanding reduced extension terminating in an enlargement, said enlargement being of a diameter in excess of the width of the slot in the arm, said slot of the arm having a portion enlarged to permit the enlarged end of the bolt to pass therethrough, and means carried by the second member for limiting the swinging movement of the second member and the arm carried thereby in a direction toward the door opening.

2. In combination with a wall having an opening, a swinging closure member therefor, a member rotatably supported by the wall adjacent to the opening, an elongated arm pivotally connected with said second member, said arm having swinging movement about its pivot in a direction angular to the swinging movement of the second member about its pivot, a sliding bolt carried by the closure member, said arm being provided with an elongated slot through which the bolt is adapted to extend when projected, said projected portion of the bolt comprising an outstanding reduced extension terminating in an enlargement, said enlargement being of a diameter in excess of the width of the slot in the arm, said slot of

the arm having a portion enlarged to permit the enlarged end of the bolt to pass therethrough, said second member being provided with an outstanding lug to provide a stop to limit the movement of said second member and the arm carried thereby toward the door opening.

3. In combination with a wall having an opening, a swinging closure member therefor, a member rotatably supported by the wall adjacent to the opening, an elongated arm pivotally connected with said second member, said arm having swinging movement about its pivot in a direction angular to the swinging movement of the second member about its pivot, a sliding bolt carried by the closure member, said arm being provided with an elongated slot through which the bolt is adapted to extend when projected, said projected portion of the bolt comprising an outstanding reduced extension terminating in an enlargement, said enlargement being of a diameter in excess of the width of the slot in the arm, said slot of the arm having a portion enlarged to permit the enlarged end of the bolt to pass therethrough, said second member and arm having means coacting to limit the upward swinging movement of the arm.

4. In combination with a wall having an opening, a swinging closure member therefor, a member rotatably supported by the wall adjacent to the opening, an elongated arm pivotally connected with said second member, said arm having swinging movement about its pivot in a direction angular to the swinging movement of the second member about its pivot, a sliding bolt carried by the closure member, said arm being provided with an elongated slot through which the bolt is adapted to extend when projected, said projected portion of the bolt comprising an outstanding reduced extension terminating in an enlargement, said enlargement being of a diameter in excess of the width of the slot in the arm, said slot of the arm having a portion enlarged to permit the enlarged end of the bolt to pass therethrough, and a spring member bearing against a peripheral portion of the second named member.

In testimony whereof I hereunto affix my signature.

JOHN PATRICK GRIMLEY.
